(57) **CLAIM**

The ornamental design for a bandana assembly as shown and described.

DESCRIPTION

FIG. 1 is a top plan view of a first embodiment of a bandana assembly, showing the claimed design;

FIG. 2 is a right side view thereof;

FIG. 3 is a first end view thereof;

FIG. 4 is a second end view thereof;

FIG. 5 is a top plan view of a first part of a first embodiment of the bandana assembly, shown in isolation;

FIG. 6 is a left side view thereof;

FIG. 7 is a right side view thereof;

FIG. 8 is a first end view thereof;

FIG. 9 is a second end view thereof;

FIG. 10 is a top plan view of a second part of a first embodiment of the bandana assembly, shown in isolation;

FIG. 11 is a right side view thereof;

FIG. 12 is a first end view thereof;

FIG. 13 is a second end view thereof;

FIG. 14 is a top plan view of a second embodiment of a bandana assembly, showing the claimed design;

FIG. 15 is a right side view thereof;

FIG. 16 is a top plan view of a third embodiment of a bandana assembly, showing the claimed design;

FIG. 17 is a right side view thereof; and,

FIG. 18 is a top plan view of a fourth embodiment of a bandana assembly, showing the claimed design.

The dashed broken lines in the figures show portions of the bandana assembly that form no part of the claimed design. The pairs of closely adjacent wavy broken lines in FIGS. 1, 2, 5-7, 10, 11, and 14-18 show a symbolic break in the length of the bandana assembly. The appearance of any portion or length of the bandana assembly between the wavy break lines forms no part of the claimed design.
